UNITED STATES PATENT OFFICE.

LOUIS K. DENNIS, OF PIERRE, SOUTH DAKOTA.

WAGON-POLE TIP.

Application filed January 15, 1924. Serial No. 686,310.

To all whom it may concern:

Be it known that I, LOUIS K. DENNIS, a citizen of the United States, residing at Pierre, in the county of Hughes and State 5 of South Dakota, have invented certain new and useful Improvements in Wagon-Pole Tips, of which the following is a specification.

This invention relates generally to wagon 10 poles and has more specific reference to a tip therefor, the primary object of the invention residing in the provision of such a tip that includes means for effectively maintaining the neck yoke ring of the animal 15 harness in permanent engagement with the end of the pole for thereby preventing any accidental displacement of the same.

An additional object of the invention resides in the provision of such a wagon pole 20 tip whereby the means for retaining said neck yoke in positive engagement with the end of said pole is prevented from becoming accidentally released and thereby allowing said ring to become disengaged from 25 the end of the pole.

An additional object of the present invention resides in the provision of such a device that may be readily and cheaply applied to practically all types of wagon poles now employed and wherein the nature of the same is 30 such as to operate effectively under all conditions.

With the above and other objects in view as the nature of the invention will be better 35 understood. The same comprises the novel form, combination and arrangement of parts hereinafter more fully described, shown in the accompanying drawing and claimed.

In this drawing wherein like reference 40 characters indicate corresponding parts throughout the several views.

Figure 1 is a side elevational view partly in cross section, of a wagon pole tip constructed in accordance with the present invention, the same being shown as actually applied to the end of a conventional form 45 of wagon pole,

Figure 2 is a detail transverse sectional view taken substantially upon the line 2—2 50 of Figure 1, and

Figure 3 is an enlarged perspective of the retaining bolt element of the present invention.

Now having particular reference to the 55 drawing, 5 designates a wagon pole that is equipped at its forward end with a guard

iron or strap 6 having its intermediate or rounded portion projecting beyond the tip of the pole so as to form a ring or eye 7 for an obvious purpose. 60

The major portion of this guard iron or strap is of conventional form. That is, the same embodies a relatively U-shaped strap member adapted for permanent positioning upon the end of said pole, the same being 65 secured thereto through the medium of a desirable number of bolt and nut connections 8.

The arm member of this guard iron or strap upon the under-side of said pole 5 is 70 formed intermediate its ends with a pendant U-shaped portion 9, the parallel leg portions of which are formed with registering openings through which extends a relatively elongated retaining bolt 10. The rear end 75 of said retaining bolt 10 is equipped with a stop nut 11 while the front end of said bolt extends considerably forwardly of said U-shaped portion 9 and is bent upwardly at this end for providing a retaining finger 12 that preferably engages said guard iron or strap when this bolt is in the position shown in Figure 1.

The opening in the foremost parallel leg 80 of said U-shaped portion is of key-shape as clearly shown in Figures 1 and 2, and adapted for engagement within the slotted portion of this opening is a lug 13 formed upon said retaining bolt 10 for preventing 85 when this bolt is in the locking position 90 shown in Figure 1, the bolt from being accidentally or even manually turned.

For maintaining this bolt in its foremost position for obviously retaining the neck yoke ring over the end of the pole and between said guard iron or strap and the retaining bolt 10, there is provided an expandable coiled spring 14. This coiled spring 14 encircles the retaining bolt at a point between the parallel leg portions of 95 the U-shaped element 9. 100

From the foregoing it will at once be obvious that in order to place the neck yoke ring upon the end of the pole or to remove the same therefrom, it will be necessary to manually retract the bolt 11 after which the same may be rotated for consequently swinging the finger 12 downwardly away from the end of the pole. 105

The specific operation together with numerous advantages of a wagon pole tip of this character will be readily appreciated by 110

those skilled in the art, and even though I have herein set forth the most practical embodiment of the invention, it is nevertheless to be understood that minor changes may 5 be made therein without departing from the spirit and scope of the appended claim.

Having thus described my invention, what I claim as new, and desire to secure by Letters Patent, is:—

10. A wagon pole tip including a strip having end portions adapted to be applied to the opposite sides of the pole, one end portion of the strip being provided at a point between its ends with a U-shaped bent portion, 15 one side of the U-shaped bent portion being provided with a key-hole slot and the opposite side being provided with an opening, a bolt passing through the opening and the key-hole slot and turnable therein, and hav-

ing an end portion projecting forwardly of 20 the U-shaped bent portion, said forwardly projecting portion of the bolt having an outwardly curved extremity, the bolt being provided at a point between its ends with a lug adapted to enter the key-hole slot, a 25 member at the rear end of the bolt and adapted to bear against the outer surface of that side of the U-shaped portion which is provided with the opening, and a spring 30 in the U-shaped bent portion coiled around the bolt and having one end bearing against the side of the U-shaped bent portion provided with the opening and the other end bearing against the lug for normally holding the lug in the key-hole slot.

In testimony whereof I affix my signature.

LOUIS K. DENNIS.
